PAIR OF SPECTACLES

Robert H. Ramp, Pittsford, N.Y., assignor to Bausch & Lomb Incorporated, Rochester, N.Y., a corporation of New York

Filed June 15, 1965, Ser. No. 85,753

Term of patent 14 years

(Cl. D57—1)

FIG. 1

FIG. 2

FIG. 3

FIG. 1 is a front view of a pair of spectacles, showing my new design;

FIG. 2 is a side view of said spectacles taken from the left side thereof as viewed in FIG. 1, the side not shown having substantially the same appearance as the side shown; and

FIG. 3 is a top plan view of said spectacles, the temple being broken away for convenience of illustration.

My design for the pair of spectacles disclosed is characterized by the configuration of the beveled portions proximate to the ends of the frame portion thereof, the said portions tapering outwardly along the top and front then downwardly along the sides and merging with the frame at the bottom, as indicated.

I claim:

The ornamental design for a pair of spectacles, substantially as shown and described.
